(57) CLAIM

The ornamental design for a cover for motor vehicles, as shown and described.

DESCRIPTION

The patent or application file contains at least one drawing executed in color. Copies of this patent or patent application publication with color drawing(s) will be provided by the Office upon request and payment of the necessary fee.

1. Cover for motor vehicles

1.1 : Front

1.2 : Enlarged

1.3 : Enlarged

1.4 : Enlarged

1.5 : Left

1.6 front perspective

1.7 rear perspective

1.8 front

1.9 front left

1.10 right

A protective cover for motor vehicles with seven red and six white alternating stripes in the central region; both sides of the cover are blue-based with a white five-pointed star pattern; there are two hanging ribbon-like decorative elements on the front of the cover; the left ribbon is red with a text "remove before flight" written with white special font, the right ribbon is blue with a text "Magic Carpet" written with white special font.
